(57) **CLAIM**

The ornamental design for an electronic cigarette with control, as shown and described.

DESCRIPTION

FIG. 1 is a rear perspective view.

FIG. 2 is a front perspective view.

FIG. 3 is a right view.

FIG. 4 is a top view.

FIG. 5 is a bottom view.

FIG. 6 is a rear view; and,

FIG. 7 is a front view.

The broken lines shown in the drawing illustrate portions of the electronic cigarette with control that form no part of the claimed design.
